UNITED STATES PATENT OFFICE.

THOMAS E. MURRAY, JR., OF BROOKLYN, NEW YORK.

RADIATOR.

Application filed May 12, 1927. Serial No. 190,687.

In certain previous applications of myself and others there are described radiators comprising a horizontal steam pipe, electric heater or similar high temperature heating element to which is applied a radiating structure of extended area in the form of transverse vertically extending fins forming flues either closed or partly closed to facilitate circulation of the heated air, and made generally of 5 copper so as to effect a very rapid transfer of heat from the heating element to the surrounding air. The present invention relates primarily to radiators of this class, and is applicable to a variety of radiators both with- 10 in and without the class referred to.

The accompanying drawings illustrate embodiments of the invention.

Fig. 1 is a plan and Fig. 2 a front elevation of a radiator;

Fig. 3 is a half plan and a half section of a terminal fitting;

Fig. 4 is a half plan and a half section of a coupling between two radiator units;

Fig. 5 is a transverse vertical section of 25 a radiator, encased;

Fig. 6 is a similar view of a modification;

Fig. 7 is an oblique view of the principal parts of a radiator;

Fig. 8 is an oblique view of the same, en- 30 cased;

Fig. 9 is a plan view of the principal parts of the same;

Figs. 10 and 11 are transverse vertical sections of different types of radiator, encased.

The principal parts of the radiator are one or more steam pipes or similar heating elements embraced by a radiating structure forming flues which heat the air and induce a strong draft of air through them.

By the present invention radiators of this and similar constructions may be manufactured more cheaply and made to work more efficiently.

For this purpose, the complete radiator is 45 made by assembling units which are separately manufactured. These units are made in such different sizes and with such connecting provisions that they may be assembled to make a complete radiator with practically any 50 desired capacity and any desired length,

width and height to fit it with advantage to the space available.

In Figs. 1 and 2, for example, I have shown a radiator made of units of two sizes, the units 1 being, for example two feet long, and the 55 units 2 being three feet long, each unit being about three inches high and three inches wide. Two such units connected end to end make the radiator approximately five feet long. These are duplicated in plan to give a 60 radiator a little over six inches in width. They are also duplicated in elevation (Fig. 2) so as to make the radiator somewhat over six inches in height. The only difference between the units 1 and 2 is in their length. 65 With two such units we can provide a radiator of any desired length in feet above the minimum length of two feet and having any desired number of pipes in height and in width.

Each unit comprises a steam pipe 3 to the front and back of which are applied plates corrugated in horizontal section to form outer and inner narrow plates 4 and 5 connected by inclined plates 6. The inner corrugations are pressed out as at 7 (see Figs. 9 and 10) to embrace the steam pipe and are pressed firmly against the latter and soldered or otherwise united thereto or welded, riveted or bolted to each other to make an intimate heat 70 conducting joint of considerable area between each plate 4 and the pipe. In the finished structure, therefore, the outside plates 4 of the corrugations form with the adjoining plates 6 flues which are closed except at the 75 top and bottom and which extend beyond the pipe above and below so as to induce a draft or circulation of the heated air which draft is the more rapid as the flues are longer. Instead of steam pipes, electric heaters may be 80 substituted, or other heating elements. A single heating element for each unit is preferred, for reasons stated hereinafter, but certain of the advantages of the invention 85 may be realized by using a plurality of heating elements in each unit.

In Fig. 7, I have shown similar units of 90 different dimensions, three such units being assembled, one above the other to make a radiator of the given length, of the height of 100

three pipes and of the width of one. At the ends where there is no pipe connection, stiffening plates 8 and 9 are used; and various other styles of support may be provided for holding the several units in the desired relative positions.

The pipes may be connected by fittings of various sorts. I have illustrated certain special fittings for the purpose in Figs. 3 and 4.

- 10 In Fig. 3 the tube 3 has its end expanded to form a flange which engages a shoulder of an internally threaded nut 10 which is adapted to receive a fitting 11 that is threaded for coupling to a steam pipe such as 12, Fig. 2, 15 (or to a cross-coupling 13 which in turn is threaded to the steam pipe 12). Fig. 4 shows a linear connection between the pipes of two units, the pipes 3 being flanged to engage the nuts 10 and the latter being screwed on to a 20 thimble 14. Fig. 1 shows the coupling nuts 11 at the ends of the radiator threaded to the ends of a fitting 13. The vertical connection between units may be by a simple bend 15, Fig. 2, threaded to the outer nut of the cross- 25 connection 13. Thus in the radiator of Figs. 1 and 2 the pipes and the units are in series vertically with the discharge end of one course communicating with the admission end of the next lower course, while the horizontal ar- 30 rangement is a parallel one, the two pipes taking their steam from a common header at one end and discharging into a header at the opposite end. Such parallel arrangements and series arrangements may be varied ac- 35 cording to circumstances and known principles of radiator design.

In practice it is probable that more than two lengths would be made in each type of basic unit in order to limit the number of 40 linear couplings required in making up a long radiator, and in order to make it possible to assemble radiators in lengths differing by less than one foot, which was the minimum permissible variation in the example given 45 above. But the number of basic units need not be large. The manufacture can be planned for a large quantity production of a few simple standard units from which a great variety of finished radiators can be assembled.

50 There are advantages in making each unit of a single steam pipe, with corrugated plates, which though the flues extend beyond the pipe so as to secure the best heating effect and induced draft, yet are comparatively narrow in the vertical dimensions.

First there is an advantage in economy of manufacture. The thin copper sheets which I prefer to use can be bought much more cheaply per pound in narrow strips than in 60 wide sheets. This is due to the comparative ease with which a narrow strip can be rolled down to a thin cross section. The narrow strip copper is also regularly manufactured and sold in coils or rolls which are easily handled and cut in continuous pieces of any

desired length. In production the strip copper can be fed through a rapidly acting machine to form it to the corrugated shape shown or to similar shapes, from which corrugated strip any required number of corrugations may be cut to form a unit of desired length. There is, therefore, very little handling and no waste of material.

Secondly, there is an advantage in operation in units of this comparatively slight 75 width having a single heating element. Radiators of this general type, particularly when made with copper plates or flues, heat the air so rapidly as to be most efficient when the height or length of the air flues is com- 80 paratively small. For example, in certain tests, a radiator with flues 21 inches high caused a rise in temperature within the bottom fifth of the height equal to nearly one- 85 half the total rise in passing through the whole flue. Similarly the second fifth of the flue height raised the air temperature approximately one-half of its remaining total rise, and so on. This advantage of short unit flues is utilized in the radiator of a previous 90 application of Phelps No. 66,444 of November 3, 1925, in which, however, separate bodies of air are heated in the separate units.

I propose to pass the air from a lower unit through the flues of the next higher unit, preferably with a space between the two to take in additional air. This simplifies the construction. And I have found that the supply of fresh air for the upper section can be heated efficiently at the same time that the warm air from the lower section is also passing through the upper one. The manner in which this arrangement acts is illustrated in Fig. 5.

As the air passes up through the lower section, at the point indicated by the arrow 16, 105 it acquires an increasing velocity so that at the point 17 the same column of air requires less space in the cross-section. Consequently fresh air is sucked in as indicated by the arrow 18, and this is in the form of a shell or 110 thick film around the hotter air at 17, and being so positioned it is next to the radiating surface of the plates 4 and 6 so that the latter transfer the heat rapidly to the cooler air.

For a third unit above the second, the same 115 increase of velocity and the same capacity for sucking in and heating an additional volume of air would be repeated. This operation has been demonstrated by observing the flow of smoke through the flues. Further positive evidence of the addition of cool air to the column flowing through each successive unit is in the fact that the average temperature of the air discharged from the bottom row of flues is but a few degrees 120 lower than that of the air discharged from the next flue above it; and that where additional units are provided above the first two the temperature of the air leaving the succeeding flues is substantially the same as 125 130

that leaving the second flue. Tests show that each unit does approximately ninety percent as much work as that immediately below it. Therefore cool air must be entering at each level in addition to the heated air from below. Also if each unit is ninety percent as efficient as that directly below it, the newly admitted cool air must have been in contact with the surface of the radiating structure.

Where radiators of this type have been made with several steam pipes one above another, embraced by flues which are continuous from bottom to top, each pipe was found to do only from sixty to seventy percent as much work as the pipe immediately below it. The admission of fresh air at the various levels is, therefore, a distinct benefit.

The same effect can be secured by making the radiator as in Fig. 6 with the radiating structure continuous through a height of two or more pipes with wide openings 19 at the sides for admission of fresh air at points between the levels of the two pipes 3. The air currents are indicated by arrows 16, 17 and 18, corresponding with those of Fig. 5.

Radiators of the style described may be used with or without an enclosing casing. Such a casing is indicated at 20 in Fig. 5 with an open bottom and with openings 21 at the sides for admission of fresh air and 22 at the top for the escape of heated air. A similar casing is indicated in Fig. 8 for the radiator of Fig. 7, having side walls 23 with openings at the sides shielded by flanges 24 and with openings 25 at the top.

The radiator of Fig. 5 has the flues in successive units directly in line with each other. According to Figs. 9 and 10, the flues 26 of the successive units are offset from each other in the longitudinal direction, so that each flue in any section receives only part of the warm air rising from any flue in the next section below. With the aid of the surrounding casing, however, practically the entire area operates in the manner of closed flues of the full height of each unit.

The successive units may also be offset laterally. I have shown such an arrangement in Fig. 11. There is an enclosing casing 27 with an opening shielded by a flange 28 at the front and a wide opening 29 at the rear. In this case the warm air from the right-hand flues of the lowest section pass through the left-hand flues of the next section and thence through the right-hand flues of the third section; the flues at the outer sides in each section operating largely independently of each other. Various other arrangements of the flues may be provided.

The radiator may be equally used for cooling air by circulating cold brine or the like through the pipes so that the latter become a heating element only in the negative sense, that is, they extract heat from the radiating

structure and induce a flow of the cool air downward through the flues similar to the upward circulation of the air induced by the passage of steam through the pipes.

Various modifications may be made by those skilled in the art without departing from the invention as defined in the following claims.

What I claim is:

1. A radiator for heating air comprising a plurality of separately formed units each including a heating element and a radiating structure forming vertical flues closed in cross-section adapted to accelerate the vertical flow of the heated air, said units being arranged in vertical alinement with each other.

2. A radiator made up of a plurality of units assembled together, each unit including a heating element and a radiating structure forming flues, said units being arranged in line with each other in the direction of flow of the heated air with the flues of one unit located in position to receive heated air from the flues in another unit.

3. A radiator made up of a plurality of units assembled together, each unit including a heating element and a radiating structure forming flues, said units being arranged in line with each other in the direction of flow of the heated air with the flues of one unit located in position to receive heated air from the flues in another unit with a space between such two units for the admission of fresh air.

4. A radiator made up of a plurality of units assembled together, each unit including a heating element and a radiating structure forming flues, vertical flues closed in cross-section so as to accelerate the vertical flow of the heated air, the flues of one units being directly in line with the flues of another so as to receive all the heated air therefrom and to induce an increased velocity of such columns of heated air, and the flues of the first named unit arranged to receive additional fresh air.

5. A radiator including in combination a plurality of separated heating elements and a radiating structure forming flues extending transversely across said heating elements with openings for the admission of fresh air to the flues between the heating elements.

6. A radiator comprising a plurality of separate units each including an elongated heating element and a radiating structure, said units being arranged alongside of each other in the direction of the length of the heating elements.

7. A radiator comprising a plurality of units assembled together each unit including a heating element and corrugated plates applied to the opposite sides thereof to form flues at the inner sides of said plates, the flues of different units being in line with each other and spaced apart, and a casing enclosing the

radiator and forming flues on the outer sides of the corrugated plates, said casing being open at the bottom and also at points adjacent to the space between the units to admit

5 fresh air.

8. A radiator comprising a plurality of separate units assembled together each unit including an elongated heating element and a

radiating structure extending transversely thereto, said units being of different lengths 10 in the direction of the length of the heating elements.

In witness whereof, I have hereunto signed my name.

THOMAS E. MURRAY, JR.
